ADJUSTABLE STOP PIN FOR ROUTERS

Charles L. White, Thomasville, N. C., and Gustave T. Johnson, Beloit, Wis., assignors to Yates-American Machine Company, Beloit, Wis., a corporation of Delaware

Application December 23, 1933, Serial No. 703,698

5 Claims. (Cl. 144—145)

This invention has to do with wood working machines of the type known as routers, and is particularly concerned with the means employed in such machines for guiding the pattern with respect to the cutter when the machine is being used as a shaper.

Heretofore it has been the practice to equip routers with a fixed guide pin for this purpose, the pin being mounted on the table of the machine in alignment with the axis of the cutter, where it is intended to serve as a stop against which the edge of the shaping pattern is guided. This fixed pin arrangement has not been entirely satisfactory, however, and has resulted in a rather high maintenance expense for the cutters and the patterns, due partly to the differences in the diameters of the cutters used and also in some instances to the performance of shaping operations on oversize work.

The object of the present invention is to provide an improved form of pattern guiding means which can be readily adjusted to compensate for all the variable factors met with in connection with the operation of a shaper and which will result in a substantial reduction in the maintenance expense for the cutters and patterns.

The improved pattern guiding means consists of a pin which is movable radially of a disk, which disk is set into an aperture in the top of the table of the router and is movable about its own axis, in combination with means for locking both the pin and the disk in any desired position of adjustment.

While the foregoing statements are indicative of the nature of the invention, other objects and advantages will be apparent to those skilled in the art upon a full understanding of the construction, arrangement and operation of the improved guiding means.

A preferred embodiment of the invention is presented herein for the purpose of exemplification, but it will of course be appreciated that the invention is capable of embodiment in other structurally modified forms coming equally within the scope of the appended claims.

In the accompanying drawing:

Fig. 1 is a perspective view of the upper portion of a router, showing the table of the router equipped with the improved pattern guide;

Fig. 2 is a plan view of the guide; and

Fig. 3 is a sectional view of the guide, taken on the line 3—3 of Fig. 2.

The improved guide, which is shown in Fig. 1 mounted in the work-supporting table 10 of a router 11, includes a flat circular disk 12, a

bolt 13 with a special rectangular wedge head 14, a rectangular wedge block 15, a cylindrical guide collar 16, a nut 17, and an adjusting screw 18 with a knurled finger wheel 19.

The disk 12 is seated in a circular aperture 20 in the table 10, with the top of the disk flush with the top of the table, and with the center of the disk directly beneath the center of the spindle 21 for the shaping cutter 22. The disk 12 is supported in the aperture 20 by means of a small annular shoulder 23 on the edge of the disk which rests upon a correspondingly shaped annular shoulder 24 in the edge of the aperture. The disk is provided with a slot 25 which extends diametrically through the disk from one edge to a point closely adjacent the other edge. This slot permits the disk to be expanded into firmly clutched engagement with the aperture in the table, while the spaced parallel edges 26 of the slot constitute gibbed ways for the support and movement of certain of the other parts of the assembly. The upper and lower portions of the edges 26 of the slot are beveled to conform respectively with the wedge shaped portions of the block 15 and bolt 13 head 14.

The bolt 13 extends upwardly through the slot 25, with the wedge portions of the head 14 of the bolt in engagement with the lower beveled edge portions of the slot. The block 15, which is apertured, fits over the bolt 13 in wedged engagement with the upper beveled edge portions of the slot. The guide collar 16 is mounted on the bolt 13 above the block 15, and the nut 17 is screwed down on the upper threaded end of the bolt in engagement with the collar.

The adjusting screw 18 is positioned horizontally in the center of the slot 25 and is threaded through a threaded aperture 27 in the head 14 of the bolt. The screw 18 is provided at one end with a plain shank portion 28 which is journaled in an aperture 29 formed in the narrow bridge portion 30 of the disk. The screw is held against endwise movement by having the end 31 thereof upset. The finger wheel 19 is mounted on the screw in an enlarged portion 32 of the slot 25 at the closed end of the latter.

In order to change the position of the guide collar 16, it is merely necessary to loosen the nut 17, whereupon the finger wheel 19 can be rotated to cause the collar 16 to travel longitudinally of the slot 25, and the disk 12, with all of the parts carried by the same, can also be turned as a unit if desired, to effect a further compound adjust-

ment. One off-center position of adjustment for the collar 16 is shown in dotted lines in Fig. 2. To lock all the parts in any position of adjustment, it is merely necessary to tighten 5 up the nut 17 again.

We claim:

1. In a wood working machine, the combination with a work-supporting table, and a shaping cutter above the table, of a disk rotatably mounted in an aperture in the table, a pin movable radially of the disk, and means for locking the pin and disk against movement in any position of adjustment.
2. In a wood working machine, the combination with a work-supporting table, and a shaping cutter above the table, of a disk seated in an aperture in the table and provided with a slot which extends diametrically of the disk from one edge to a point adjacent the opposite edge, a wedge positioned in the slot for expanding the disk into clutched engagement with the edge of the aperture, a guide mounted on the wedge, means for adjusting the position of the wedge longitudinally of the slot, and means for tightening the wedge to lock the disk and guide in any desired position of adjustment.
3. In a wood working machine, the combination with a work-supporting table, and a shaping cutter above the table, of a disk seated in an aperture in the table and provided with a slot which extends diametrically of the disk from one edge to a point adjacent the opposite edge, a bolt extending upwardly through the slot and provided at its lower end with a wedge-shaped

head for clamping engagement with the lower edges of the slot, an apertured wedge block mounted on the bolt for clamping engagement with the upper edges of the slot, a guide collar mounted on the bolt, a nut on the bolt above the collar, an adjusting screw journaled in the disk at one end of the slot in threaded engagement with the head of the bolt, and a knurled finger wheel on the screw for rotating the latter to move the bolt and the other parts longitudinally 10 of the slot.

4. In a wood working machine, the combination with a work-supporting table, and a cutter above the table, of a guide on the table beneath the cutter, an adjusting screw connected with 15 the guide beneath the upper surface of the table for moving the guide into any one of several positions with respect to the cutter, and a finger wheel on the screw beneath the upper surface of the table for rotating the screw to move the 20 guide.

5. In a wood working machine, the combination with a work-supporting table, and a cutter above the table, of a guide on the table beneath the cutter, an adjusting screw connected with 25 the guide beneath the upper surface of the table for moving the guide into any one of several positions with respect to the cutter, a finger wheel on the screw beneath the upper surface of the table for rotating the screw to move the 30 guide, and means for locking the guide against movement in any position.
